TYPEWRITING MACHINE

Carl R. Mabon, Niagara Falls, N. Y., assignor to
 Gilman Fanfold Corporation, Niagara Falls,
 N. Y., a corporation of Delaware

Application September 12, 1936, Serial No. 100,521

20 Claims. (Cl. 197—133)

This invention relates to improvements in strip feeding mechanism for feeding, controlling and guiding the record strips in their passage over the platen of writing machines or typewriters of the type having paper or platen carriages which are shiftable for letter spacing.

It is an object of the present invention to provide paper feeding means independent of contact with the platen and of the usual feed rollers contacting a cylindrical or rotatable platen, said paper feeding means being located to one side of the platen and, as to one important feature, comprising an endless succession of pins, a plurality of which have simultaneous engagement with 15 a plurality of holes or feed apertures in the paper supply strips to advance or pull said paper strips over the platen.

Another object is to provide means for applying improved paper strip feeding mechanism to 20 a typewriting machine wherein the paper carriage is shiftable endwise, or in letter spacing direction, the paper carriages of such machines being also customarily laterally shiftable transversely of their endwise shift for upper and lower case characters.

Another object is to provide an improved feeding means for machines of the class mentioned and constructed as a unitary device readily attachable to the paper carriage of the machine.

Another object is to provide a comparatively light weight improved feeding means which has minimum tendency to disturb the proper balance of the carriage during the shifting thereof, even though located at one end only of the carriage, 35 and which will not add unduly to the weight of the carriage and so that movement of the latter endwise and sudden stopping thereof may be accomplished without injuring the machine.

Another object is the provision of a simple and 40 efficient combined paper guiding and feed mechanism supporting frame which is shiftable with the paper carriage and effectively supports the feed mechanism and rear paper guides in operative relation and is adapted for feeding, handling 45 and guiding of paper of different widths.

Other objects and advantages will appear hereinafter.

The invention accordingly comprises the features of construction, combination of elements, 50 and arrangement of parts which will be exemplified in the construction hereinafter set forth, and the scope of the application of which will be indicated in the claims.

In the accompanying drawings forming part 55 of this specification and wherein similar reference

characters refer to similar parts throughout the several views:

Fig. 1 is a perspective view, partially diagrammatic, of the invention as applied to a typewriting machine of the character referred to;

Fig. 2 is a side view of the same, with parts broken away;

Fig. 3 is a longitudinal section of the same, with parts broken away, and showing the paper in dotted lines;

Fig. 4 is a detail section substantially on the line 4—4, Fig. 3, parts being shown as broken away, and the paper being shown in dotted lines;

Fig. 12 is a similar view showing other stationery that may be used; and

Fig. 13 is a detail section on the line 13—13, Fig. 5.

In these drawings, the numeral 1 designates generally a typewriting machine which may be of usual known construction except for the embodiment of the present invention therein. It may involve power actuation and control as in 40 the electric typewriting machine, or other power actuated machines, or it may be the ordinary manually actuated and controlled typewriting machine. The paper carriage, as the platen carriage 2 is shiftable as usual and by the usual devices, and carries the platen 3 rotatably mounted to shift with the carriage. The type bars are shown in part at 3a, the line spacing wheel 3b is controlled by a suitable line spacing pawl and a detent as customary (not shown); a finger 50 wheel for manual control of the platen is shown at 3c, and the character keys are shown in part in dotted lines at 3d.

Located to one side of the platen and independent of contact therewith is the paper feeding 55

mechanism, comprising an endless chain the alternate links 4 of which each has a pin 5, so as to provide an endless succession of pins 5, a plurality of which have simultaneous engagement with a plurality of feed apertures 6 of paper record strips 7 to pull said strips from around the platen. These pins may be of cylindrical form with rounded tips, as shown, although other forms may be used in some cases, and the strip engaging and feeding sections of the pins are disposed in a plane located inside the pitch-line of said chain or line of centers of the pivots of said chain with the terminals or tips of the pins in the plane substantially of said pitch-line or line of centers, whereby the engagement and disengagement of said pins with respect to said apertures will be accomplished without undue disturbance or mutilation of the paper margins around said feed apertures and the registry of the superposed paper supply strips will be effectively attained or maintained in the passage thereof through the machine. Inasmuch as the construction of the chain and the pins and their relation to each other and to the sprocket wheels 12, hereinafter mentioned, is the same, as described in applicant's prior applications, Serial No. 54,102, filed December 12, 1935 and Serial No. 96,516, filed August 17, 1936, to which reference may be made for more detailed description, only a brief description of the chain and pins is included herein. This construction of the chain and pins as fully described in the said prior pending applications is generically claimed therein, while the invention of the present application is wholly concerned with improvements over the prior applications, the claims of the present application being confined to the improvements.

This paper feeding means is embodied in a self-contained unit readily attachable to the paper carriage of the machine, comprising parallel, spaced, rigid, metal frame blocks or bearing blocks or brackets 8 and 8', a transverse rigid part 9 having at one end an extension 10 forming a longitudinal support or track for those links of said chain the pins of which are engaged with the feed apertures of the paper record strips to effect feeding, the parallel stub shafts 11 of the end sprockets 12 which engage the pivots 4b of said chain having ballbearings located within recesses 14 at each end of each of said bearing blocks 8 and 8', each sprocket wheel 12 being in duplicate and fast to a sleeve 12a, set screws 12b engaging aligned apertures of the hubs of said wheels and said sleeve serving to make the same fast to said stub shafts, so that these parts rotate in unison.

The links 4 of the chain which carry the pins 5 have each a pin support or supporting part 4a, laterally projecting from the links, and which also supports the margin of the paper to be fed, and each pin supporting link may be bent from integral metal to provide side members of similar construction, an outer transverse member connecting said side members and said laterally projecting part or member, the transverse pivots 4b, connecting said links to the alternate links 4c, having bearings at their ends in said side members of the links and engaging the teeth of the duplicate sprocket wheels 12.

The aforesaid unit also comprises means to guide the paper record strips and to maintain the same with a plurality of the feed apertures thereof in simultaneous engagement with a plurality of said pins, said means comprising an arm or plate 17, pivoted at its outer end at 18

to a support 19, and having an inner, slotted, strip guide and retainer part or foot 20, the slot 21 of which is long enough to receive the rounded tips of those pins of the chain which are in engagement with said feed apertures of the paper 5 and lie along the tangential or elongated path of the chain between the longitudinally spaced sprocket wheels 12. A spring 22 is secured to said plate by bolt of clip 22', and is curved upwardly over and slidably engages a roller 23 of 10 said support, to thereby hold said spring tensioned to press the slotted foot 20 of said plate towards the paper record strips until engaged by integral stop 19a of said support, said plate being adapted to be raised to inoperative position as 15 seen in Figures 5 and 10 against the tension of its spring. The support 19 is attached to the top of the transverse part 9 by suitable means, such as screws, and the retainer is thus mounted on the bearing block 8'. 20

A single attachment or fastener bolt 15 for said unit engages center perforations 16 of said blocks 8 and 8', and is provided with the nut 15a to clamp the same securely in position relative to a standard or other support 33 to be described and 25 the upper end of which lies between said brackets, said bolt passing through an opening in said standard, a suitable spacing collar 15b being located between one of said brackets and said standard, as seen in Fig. 5. 30

The endless chain of the paper feeding means is shown as driven by sprocket chain 24, engaging a sprocket wheel 25 on the platen shaft and a sprocket wheel 26 on the shaft of the rear sprocket wheels of the paper feeding means. Or 35 a gear drive of any suitable type may be substituted for the chain and sprocket drive.

The paper feed rollers 27 found in usual typewriting machines, for gripping the paper to the platen are shown as shifted to inoperative position in Figure 3, as the feed mechanism disclosed herein may be used to good advantage without said feed rollers. 40

It is preferred to utilize the paper strip feed mechanism disclosed herein for the feeding of 45 continuous, paper record strips, as the record strips 7, coming from a supply at the rear of the machine. These strips also have a series of pre-formed feed apertures as 6, and whereas similar pin feed mechanism for coaction with apertures 50 at both margins of the record strips (see Fig. 12) may be used it is preferred to arrange the pin feed mechanism for coaction with but one margin of the stationery or record strip as seen in Figure 11. By so doing, practically the full width of the 5 machine is available for consideration and manipulation of the record strips, and also record strips of different widths may be employed without altering the position of the pin feeding mechanism. 55

Referring to Figure 11, a portion of the lengths 6 of three relatively superposed, continuous, record strips 7, are shown, such strip assemblage having two interleaved and also continuous transfer or carbon strips 28, the transfer strips being narrower than the record strips. In each of the 6 record strips is a row or series of feed holes or apertures 6, which are usually circular and equi-spaced along the strips, the record strips having each a series of similar printed forms underlying one another in registered or aligned relation, 7 when the feed apertures 6 of the forms are in superposed registry. There is but one series of feed apertures 6 in the record strips of Fig. 11, the carbon strips 28 being disposed laterally out of registry with the feed apertures 6, and the re- 75

spective strips 7 and 28 of Fig. 11 being not attached together and capable of relative movement.

In Fig. 12 the printed forms and feed apertures have the same relation to each other as explained in connection with Fig. 11, but in this instance the feed apertures occur at both margins of the strip. The carbon strips of Figs. 11 and 12 may be of full width and provided with feed apertures if desired. As shown in Fig. 12, staples 29 serve to attach the several superposed strips together, these attaching devices being distributed at intervals throughout the length of the assemblage of strips, and preferably being on the transverse weakening lines 30, which latter occur between each of the adjacent printed forms, so that when the tear off is made along such a line the staple will drop out. As shown in Fig. 12 the carbon sheets may be provided with arcuate central slits 31 around one side of and spaced from said staples, said slits forming part of said weakening lines, and when a tear off is made along a weakening line those parts of the carbon sheets included by said slits will remain as tabs 32, extending beyond the ends of the paper strips at the parted or torn off edge, the staples remaining in position connecting the carbon sheets so that the latter may be withdrawn all together by grasping said tabs with the fingers.

For supporting and guiding the continuous paper strips coming from a suitable source of supply at the rear of the machine, and also for supporting and positioning the pin feeding mechanism in operative relation, a device is employed which is shiftable with the paper carriage or platen carriage 2 of the machine. In the embodiment illustrated, a standard 33, being a strong and rigid plate, is carried by the platen carriage 2, being dispersed in the rear of the carriage, and may be detachably secured to the carriage 2 by screws as 34. To assist in bracing the standard 33 in position on the platen carriage and in supporting the paper strip to be fed, a second standard 35, is carried by the opposite end of carriage 2, or is spaced from standard 33, and is detachably affixed to the carriage by suitable fasteners, as the screw 36. A rearward extension of the standard 33 is provided by the strong and rigid plate 35', which is detachably affixed to the standard plate 33 by the screws 36', the plate 35' having a depending portion 47, lying close alongside the standard plate 33, with its front edge abutting the rear of the carriage 2, as indicated at 37, to assist in holding or bracing the plate 35' in position.

The bracket or bearing block 8' is disposed on the outer face of the standard 33 (see Figs. 2 and 5) and the bolt 15 passes through a fitting opening in standard 33 and through the central opening 16 in block 8'. By screwing up nut 15a, the block or bracket 8, which supports the chain of links 4, may thus be clamped to standard 33, and a suitable sleeve 15b is located between this standard and block in accordance with the desired lateral position of the block 8. At each end of block 8' is a ball bearing for rotatably supporting the respective stub shafts 11. Should the pin feeding mechanism be duplicated at the opposite end of the platen carriage, a similar mounting therefor may be employed at said opposite end. It will be seen that the plates 33 and 35' provide, in effect, a standard at one end of the platen carriage, another standard 35 being provided at the opposite end, and that the feed mechanism is so disposed that the pins travel in

a path between these two opposite standards, as also do the apertured paper strips.

For further bracing in accurate position the standard on which the series of feed pins is mounted, and in order to support certain rear paper guides and form an open or skeleton-like rear framework of relatively light weight permitting convenient manipulation and inspection of the paper strips and to permit paper strips of different widths to be utilized as desired, without adjusting the lateral position of the series of feed pins, a series of bars or rods as 40 and 40' connect the opposite standards just mentioned and, together with said standards, form a rigid, open or skeleton frame, said rods being firmly joined to the standards, and serving also to brace the standards in position. Thus there is provided an open passageway in the carriage in which the paper strips may feed past the rods 40 and 40' and around the platen 3. The bars 40 and 40' may be secured to the standards as by screws, so that they may be detached from the standards, when desired. By providing the plate 35', detachable from standard plate 33, it will be seen that the bars 40 and 40' and the rear strip-guides hereinabove described, may be detached from the machine as a unit without demounting the pin-feed mechanism, or its supporting standard 33, and it will further be seen that the pin feed mechanism as well as the rear strip-guides are readily attached to and detached from the platen carriage as a unit.

The paper guides 38, being smooth, curved, metal plates, have each lateral depending flanges 39, provided with bearing openings engaged by the lower cross rods 40, these guides being supported by and adjustable along said cross rods transversely of the machine. The upper cross rod 40', connecting said standards 35 is spaced rearwardly of the upper end of the paper feeding means and serves as a support for the paper record strips being delivered rearwardly out of the machine.

The lateral guides 38 for the paper may rest at their forward ends upon the rear ends of the usual paper table or guide 31 of the machine, to form rearward extensions of such table. These lateral paper guides have each an outer, lateral, upstanding flange 42, and as said guides are laterally adjustable, said flanges are adapted to lie close to or abut against the opposite edges of the paper record strips to assist in retaining the latter in proper position aligned or engaged with the pins of the paper feeding means during end-wise shifting of the carriage, such shifting being subject to abrupt halts which might otherwise disturb the paper strips.

In order to hold the paper record strips down to said guides, each of the lateral guides 38 may be provided with a strip smoothing and tensioning device comprising a spring clasp or a clip 44, engageable over a flange 42 of the lateral guide and having a lateral extension 43 overlying the guide 38 and adapted to rest on the paper to slightly tension and smooth the advancing paper strips. As these attachments are adjustable longitudinally of the guides they may be disposed as desired and they are also readily removable, as will be obvious. The central portions of the paper guides 38, are shown as terminating at their lower ends adjacent the inner of the lower cross rods 40. The lateral guides 38 are held in position, as laterally adjusted, by suitable means, such for instance as a cam lever 45, carried by the lateral flange 39, the cam head of which lever 75

is adapted to engage one of the lower cross rods 40. The central paper guide 38 is adapted to be easily removed from said cross rods 40 being provided with open-end slots 46 in the flanges 39 5 for this purpose, as seen in Fig. 9.

In operation, feeding and line-spacing is effected by causing the pins to move in their endless path, this being effected by driving the endless flexible band or chain of links, this chain 10 serving also as a pin-guiding member for carrying the pins in the endless path. The movements of the chain are in response to operation of the ratchet wheel 3b, which operation is effected by the customary line-space actuating 15 mechanism found in typewriting machines. The paper strips shift with the platen carriage in both letter spacing and line spacing directions, and are subject to sudden stops, especially in 20 rapid typing and shift of the platen carriage in letter spacing direction, the return shift of the carriage usually being speedy and stopping with considerable shock. By reason of these various 25 sudden shocks encountered in usual operation, the paper strips tend to be displaced both laterally and in vertical direction with consequent tendency to move on the feed pins laterally and up and down. It makes for accurate feeding or line-spacing to have the apertures in the paper strips engage the pins toward their bases or roots 30 and the construction described promotes such engagement notwithstanding the sudden halts and shocks. Furthermore the construction for supporting and guiding the paper through the platen carriage to the feed pins, being disposed 35 laterally of the pin feed mechanism and its driving devices, has a counterbalancing effect relative to the weight of the feed mechanism at one side only of the paper, and it lessens the tendency otherwise of the carriage to tilt, and thus 40 assures easy shifting in letter spacing directions, and at the same time provides for the efficient support and feeding of the strips through the platen carriage. The difference in diameter between the apertures and the feed sections of the 45 pins is preferably very small, a tolerance of but one sixty-second of an inch being very practical. Notwithstanding this small or no difference in relative diameter, the pins register accurately with the apertures and there is practically no 50 injury to the strips or the margins of the apertures, either during the acts of engaging or disengaging. The pins may be spaced apart on the pin-guiding chain the same as are the apertures in the paper strip, as illustrated.

Having described my invention, what I claim as new and desire to secure by Letters Patent is:

1. In a typewriting machine having a longitudinally shiftable paper carriage and a platen mounted on said carriage to shift therewith for letter spacing; paper feeding mechanism independent of contact with the platen and located to one side thereof, comprising a series of feed pins adapted to enter and feed the paper, means, including a flexible member on which said pins are mounted and supports for said member cooperable to move said member and pins and to cause said pins to enter and feed the paper, the strip-engaging-and-feeding sections of the respective pins being disposed in a plane inside the pitch line of the flexible member, a plurality of said pins having simultaneous engagement with a plurality of feed apertures of said paper to pull the paper from around the platen, and means for mounting said paper feeding mecha-

nism on said carriage for shifting movement therewith.

2. In a typewriting machine having a longitudinally shiftable paper carriage and a platen mounted on said carriage to shift therewith for letter spacing; paper feeding mechanism independent of contact with the platen and located to one side thereof, comprising an endless series of feed pins adapted to enter and feed the paper, means, including a flexible member on which said pins are mounted and carrying wheels for said member cooperable to move said member and pins and to cause said pins to enter and feed the paper, the strip-engaging-and-feeding sections of the respective pins being disposed in a plane inside the pitch line of said flexible member, a plurality of said pins having simultaneous engagement with a plurality of feed apertures of said paper to pull the paper from around the platen, and means for mounting said paper feeding mechanism on said carriage for shifting movement therewith, said feed pins, flexible member, carrying wheels and mounting means being located at one end only of said carriage.

3. In a typewriting machine having a paper carriage and a platen mounted on said carriage; paper feeding mechanism independent of contact with the platen and located to one side thereof, comprising an endless series of feed pins adapted to enter and feed the paper, means, including an endless flexible member on which said pins are mounted and carrying wheels for said member cooperable to move said member and pins and to cause said pins to enter and feed the paper, the strip-engaging-and-feeding sections of the respective pins being disposed in a plane inside the pitch line of said flexible member, a plurality of said pins having simultaneous engagement with a plurality of feed apertures of said paper to pull the paper from around the platen, and means for mounting said paper feeding mechanism on said carriage, comprising an end standard and a support having spaced brackets between which fits said standard and a transverse part connecting said brackets and having an extension whereon travels said flexible member, each of said brackets having spaced bearings for the respective shafts of said carrying wheels.

4. In a typewriting machine having a paper carriage and a platen mounted on said carriage; said carriage being mounted for longitudinal shifting movement to effect letter spacing; paper feeding mechanism independent of contact with the platen and located to one side thereof, comprising an endless series of pins adapted to enter and feed the paper, means, including an endless flexible member on which said pins are mounted and carrying wheels for said member cooperable to move said member and pins and to cause said pins to enter and feed the paper, the strip-engaging-and-feeding sections of the respective pins being disposed in a plane inside the pitch line of said flexible member, a plurality of said pins having simultaneous engagement with a plurality of feed apertures of said paper to pull the paper from around the platen, and supporting devices for mounting said paper feeding mechanism on said carriage for shifting movement therewith and comprising a member whereon travels said flexible member and a slotted guide and retaining device overlying said member with the slot thereof engaged by certain of said pins, said device being also located in a

plane inside said pitch line of said flexible member.

5. In a typewriting machine having a longitudinally shiftable carriage and a platen mounted on said carriage to shift therewith; paper feeding mechanism comprising a series of feed pins adapted to enter and feed the paper, means, including a flexible member on which said pins are mounted and supports for said member cooperative to move said member and pins and to cause said pins to enter and feed the paper, and means for mounting said paper feeding mechanism on said carriage comprising an end standard and a device having spaced brackets between which fits said standard and a transverse part connecting said brackets and having an extension whereon travels said flexible member, each of said brackets having spaced bearings for said supports.

6. In a typewriting machine having a longitudinally shiftable carriage and a platen mounted on said carriage to shift therewith; paper feeding mechanism comprising a series of feed pins adapted to enter and feed the paper, means, including a flexible member on which said pins are mounted and rotary supports for said flexible member cooperative to cause said pins to enter and feed the paper, and means for mounting said paper feeding mechanism on said shiftable carriage comprising an end standard and a device connected thereto and having spaced brackets between which fits said standard and a transverse part connecting said brackets and having a flexible member supporting extension whereon travels said flexible member, each of said brackets having spaced bearings for said supports, and a slotted guide and retaining device overlying said flexible member with the slot thereof engaged by certain of said pins.

7. In a typewriting machine having a longitudinally shiftable carriage and a platen mounted on said carriage to shift therewith; paper feeding mechanism comprising a series of feed pins adapted to enter and feed the paper, means, including a flexible member on which said pins are mounted and supports for said member cooperative to move said member and pins and to cause said pins to enter and feed the paper, and means for mounting said paper feeding mechanism on said carriage comprising an end standard and a device connected thereto and having spaced brackets between which fits said standard and a transverse part connecting said brackets and having an extension whereon travels said flexible member, each of said brackets having spaced bearings for said supports, and a spring impelled slotted guide and retaining device overlying said flexible member with the slot thereof engaged by certain of said pins, said device having an integral stop to limit its movement to operative position and being adjustable to inoperative position against the tension of its spring.

8. In a typewriting machine having a longitudinally shiftable carriage and a platen mounted on said carriage to shift therewith; paper feeding mechanism comprising a series of feed pins adapted to enter and feed the paper, means, including a flexible member on which said pins are mounted and supports for said member cooperative to move said member and pins and to cause said pins to enter and feed the paper, and means for mounting said paper feeding mechanism on said carriage comprising an end standard and a device having spaced brackets connected to said standard and having an extension

whereon travels said flexible member, each of said brackets having spaced bearings for said supports, paper guides spaced laterally from said paper feeding mechanism, and means for mounting said paper guides on said carriage comprising an end standard opposite said first named standard and cross rods connecting said standards and engaged by said paper guides.

9. In a typewriting machine having a longitudinally shiftable carriage and a platen mounted on said carriage to shift therewith; paper feeding mechanism comprising a series of feed pins adapted to enter and feed the paper, means, including a flexible member on which said pins are mounted and supports for said member cooperative to move said member and pins and to cause said pins to enter and feed the paper, and means for mounting said paper feeding mechanism on said carriage comprising an end standard and a device on said standard having an extension whereon travels said flexible member, paper guides spaced laterally from said paper feeding mechanism and having lateral flanges engageable with the edge portions of the paper and means on said flanges to hold the paper down to said guides, and means for mounting said paper guides on said carriage comprising an end standard opposite said first named standard and cross rods connecting said standards, and engaged by said paper guides.

10. In a typewriting machine having a longitudinally shiftable carriage and a platen mounted on said carriage to shift therewith; paper feeding mechanism comprising a series of feed pins adapted to enter and feed the paper, means, including a flexible member on which said pins are mounted and supports for said member cooperative to move said member and pins and to cause the pins to enter and feed the paper, means for mounting said paper feeding mechanism on said carriage comprising an end standard and a device on said standard having an extension whereon travels said flexible member, paper guides spaced below and laterally of said paper feeding mechanism, means for mounting said paper guides on said carriage comprising an end standard opposite said first named standard and lower cross rods connecting said standards and engaged by said paper guides, and an upper cross rod connecting said standards spaced rearwardly of the paper feeding mechanism and adapted to support paper fed out of the machine.

11. In a typewriting machine, the combination of a platen carriage movably mounted for letter spacing, a rigid skeleton frame, having standards attached to and supported by said carriage and movable therewith and spaced apart lengthwise of the platen and rods connecting said standards and bracing them in position and providing an open passageway in the carriage and past said rods for feed movement of the paper strips around the platen, strip feeding mechanism, comprising a series of strip feeding pins, mounted on one of said standards and movable in an elongated path between said standards for feeding the strips, and a strip supporting plate carried by said rods.

12. In a typewriting machine, the combination of a platen carriage movably mounted for letter spacing, a rigid skeleton frame, having standards attached to and supported by said carriage and movable therewith and positioned in rear of the platen and spaced apart lengthwise of the platen and rods connecting said standards in rear of the platen and bracing them in position and pro-

- viding an open passageway in the carriage and past said rods for feed movement of the paper strips around the platen, strip feeding mechanism, comprising a series of strip feeding pins, 5 mounted on one of said standards and movable in an elongated path between said standards and in front of said rods for feeding the strips and a strip supporting plate carried by said rods.
13. In a typewriting machine, the combination 10 of a platen carriage movably mounted for letter spacing; a rigid skeleton frame, having standards attached to and supported by said carriage and movable therewith and positioned in the rear of the platen and spaced apart lengthwise of the 15 platen and rods connecting said standards in rear of the platen and bracing them in position and providing an open passageway in the carriage and past said rods for feed movement of the paper strips around the platen, strip feeding 20 mechanism, comprising a series of strip feeding pins, mounted on one of said standards and movable in an elongated path between said standards and in front of said rods for feeding the strips and a plurality of curved, strip supporting plates carried by and adjustable relatively to each other 25 along said rods, one or more of said strips supporting plates having a flange for cooperating with the edges of the strips to guide the strips.
14. In a typewriting machine, the combination 30 of a platen carriage movably mounted for letter spacing, a standard rigidly and detachably affixed to said carriage, a plate detachably fixed to said standard and extending from said standard, a second standard detachably and rigidly affixed 35 to said carriage at a point spaced from said first mentioned standard, standard-bracing means including a brace rod connecting said extending plate to said second standard, a series of strip feeding pins, and means independent of the detachable connection between said extending plate 40 and said first mentioned standard, for mounting said series of pins on the latter standard for feeding the strip.
15. In a typewriting machine, the combination 45 of a platen carriage, a standard rigidly and detachably affixed to said carriage, a plate detachably fixed to said standard and extending from said standard, a second standard detachably and rigidly affixed to said carriage at a point spaced 50 from said first mentioned standard, standard-bracing means including a brace rod connecting said extending plate to said second standard, a series of strip feeding pins, means, independent of the detachable connection between said extending plate 55 and said first mentioned standard, for mounting said series of pins on the latter standard for feeding the strip, and strip supporting means, including a plurality of curved plates longitudinally adjustable to different positions on said standard bracing means.
16. In a typewriting machine, the combination 60 of a platen carriage, a standard rigidly connected to said carriage, bearing blocks one at each of opposite sides of said standard, parallel shafts each bearing in both said blocks at points spaced apart in direction of feed of the strip, means, including a fastener passing through said blocks and standard, cooperable to hold said blocks in stationary position on said standard, and means, 65 including sprocket wheels on said shafts and an endless pin-guiding chain surrounding one of said blocks and driven by one of said sprocket wheels, cooperable to feed the strip.
17. In a typewriting machine, the combination 5 of a platen carriage, a standard rigidly connected to said carriage, bearing blocks one at each of opposite sides of said standard, parallel shafts each bearing in both said blocks at points spaced apart in direction of feed of the strip, means, including 10 a fastener passing through said blocks and standard, cooperable to hold said blocks in stationary position on said standard, means, including sprocket wheels on said shafts and an endless pin-guiding chain surrounding one of said blocks 15 and driven by one of said sprocket wheels, cooperable to feed the strip, a strip retainer device shiftable into and out of retaining position, and means shiftably connecting said retainer device to the other bearing block. 20
18. In a typewriting machine, the combination of a platen carriage shiftable in letter spacing direction, a standard carried by one end of said carriage and shiftable therewith, strip feed mechanism, including a series of feed-pins movable in an endless, elongated path mounted on and shiftable with said standard, and a strip guiding and supporting device, having a part disposed laterally of said standard and feed mechanism toward the opposite side of said carriage and 30 mounted on said platen carriage, adapted to counterbalance the weight of said standard and strip feed mechanism.
19. In a typewriting machine in combination, a longitudinally shiftable paper carriage and a 35 platen mounted thereon for shifting movement therewith, strip feeding mechanism positioned only at one side of the machine and mounted on said carriage and spaced rearwardly of said platen, said feeding mechanism including an 40 endless succession of pins positioned for feeding engagement only along one longitudinal marginal portion of the strip while the opposite longitudinal margin is free from any feeding mechanism, a flexible supporting member for said pins 45 and mounting the latter so that a plurality of the pins have simultaneous feeding engagement with the strip being fed, said flexible supporting member including pivotally connected rigid links on which said pins are respectively mounted in 50 longitudinally spaced relation, and adjustable paper guiding plates mounted on said shiftable carriage. 55
20. In a typewriting machine in combination, strip feeding mechanism including a traveling flexible feed element and strip engaging feed pins mounted thereon for feeding the strip, rotary supporting and driving members for said flexible feed element, short supporting shafts for said supporting members positioned adjacent to one 60 longitudinal edge of the strip path and terminating at their inner ends short of the opposite longitudinal edge of the strip path, bearings for said shafts at spaced parts thereof, and a supporting bracket for said feeding mechanism connected to the machine and positioned intermediate said bearings. 65
